BREAD SLICING MACHINE

Harry J. Criner, Davenport, Iowa, assignor of
one-half to A. G. Bush, Davenport, Iowa

Application June 10, 1935, Serial No. 25,759

14 Claims. (Cl. 146—153)

My invention relates to improvements in bread slicing machines having a plurality of reciprocating slicing blades.

The objects of my invention are to provide a bread slicing machine of superior simplicity and ease of manufacture which will occupy a very small space and will have readily interchangeable slicing units so as to provide for changing the gauge or thickness of the slices of bread by a mere interchange of parts of the machine without the necessity of adjusting various parts when changing gauge.

I attain these objects by the means illustrated in the accompanying drawing, in which:—

15 Figure 1 is a vertical section of my machine on the line 1—1 of Figure 2;

Figure 2 is a rear elevation with a part of the upper and lower housings and bread table cut away and showing the interior in section on the 20 line 2—2 of Figure 1, referring to the right of Figure 1 as the rear and to the left of Figure 1 as the front;

Figure 3 is a detail showing one of the guide rolls and bearing plates bearing thereon;

25 Figure 4 is an enlarged detail plan view of a portion of the guide plate;

Figure 5 is an enlarged detail showing a portion of one of the bearing plates, 10, in section, with lug, 11, and lower end of blade, 14, secured 30 therein.

My machine comprises side frames or plates, 1, having feet, 2, formed integral therewith and having inwardly extending flanges, 1a, formed integral therewith. These side plates form closed sides for the machine and are spaced apart and held in position by lower housing plates, 26 and 26a, and by an upper housing plate, 25, preferably formed in substantially inverted U-shape, but with diverging arms. The housing plates, 26 and 26a, may be united to the flanges, 1a, by rivets, 1', bolts, or other suitable means. But I prefer to use stud bolts or set screws for this purpose, as being more readily removable.

Extending crosswise of the machine to form 45 a support for the motor are two angle irons, 20, resting upon the lower portions of the flanges, 1a, and upon these angle irons I mount the feet, 4', of the motor, 4. A motor shaft, 5, extends outwardly at each end of the motor and carries 50 at each end arms or connecting rods, 8 and 9. The arms or connecting rods, 8 and 9, are formed integral with bearing plates, 10. The bearing plates, 10, and connecting rods, 8 and 9, are arranged in substantially U-shape form and are 55 made interchangeable.

The lower ends of the connecting rods, 8 and 9, are provided with offset eccentric rings, 6 and 7, which embrace eccentrics, 6' and 7', keyed upon the ends of the motor shaft, 5. The rings, 6 and 7, are offset so as to keep the lower ends 5 of the connecting rods, 8 and 9, centered at all times to opposite sides of the center of the shaft, 5. The connecting rods, 8 and 9, have their upper portions crossed and the bearing plates, 10, stand at a substantial angle to the vertical. 10

In each of the side frames, 1, at the level of the bearing plates, 10, I mount stub shafts or pivot bolts, 13, which may be detachably secured to the side plates in any desired manner. Upon the inner end of the pivot bolts, 13, I mount 15 guide rolls, 12, which extend inwardly a sufficient distance to form a firm bearing for bearing plates, 10, at both ends thereof.

Upon the inner faces of the bearing plates I provide a series of lugs, 11. The lugs upon one 20 of the bearing plates, 10, are staggered and alternate with the lugs upon the opposed bearing plate, 10. These lugs are slotted to admit the lower ends of the cutting blades, 14, which may be secured therein by pivot pins, 11', or by any 25 other suitable means.

Brackets, 22, are formed integral with the rear flanges, 1a, of the side plates and support a transverse guide plate, 15, which may be united to the brackets by set screws, 16, or other suitable means. The guide plates, 15, are preferably formed of oilless bearing material and are provided with slots, 14', at their front edge through which the upper ends of the cutting blades 14, pass, the slots, 14', being the proper 35 width to act as guides for the cutting blades.

In the guide plate, 15, I form a plurality of bores, 19, spaced to correspond with the spacing of the slots, 14'. In these bores, 19, I secure by pressfit or other suitable means, a plurality 40 of supporting rods, 17, which project upwardly from the guide plate, 15, and the upper ends of which are bent at right angles to afford attachment for one end of a plurality of springs, 21, the lower ends of which are united severally to 45 the upper ends of the cutting blades, 14, which are adapted to exert tension upwardly on the cutting blades at all times.

A bread chute or table, 23, having downwardly extending side flanges, 24, is united to the side 50 plates, 1, by bolts, 23', the middle portion of which is slotted to provide for passage of the cutting blades, 14, but the slots in the bread plate are not to act as guides for the cutting blades, 14, nor to come in contact therewith at 55

all, as the lower ends of the cutting blades will be properly guided by the lugs, 11, and no other guide therefor will be necessary.

The bread table, 23, is preferably made of sections so that the comb-shaped middle section may be removed when necessary to change the slicing units without disturbing the front and rear sections.

It is obvious that with the U-shaped driving frames comprising the connecting rods, 8 and 9, and bearing plates, 10, formed and mounted as described, the upward pull of the cutting blades, 14, upon the bearing plates, 10, will necessarily draw the bearing faces of the plates, 10, into close contact with the guide rolls, 12, and retain them in contact therewith at all times so that no tractive means attached to the bearing plates, 10, will be necessary to draw them toward each other and keep them in contact with the guide rolls, 12.

My form of apparatus makes it a very simple matter to change the gauge of a cutting machine for slices of different thicknesses. The U-shaped frames can be readily removed from the crank shaft, 5, and the guide plate, 15, together with the supports, 17, attached thereto and the springs, 27, and the cutting blades, 14, can all be removed without detaching same from each other and a new unit or assembly having the desired spacing or gauge may then be inserted and likewise new U-shaped frames, including arms or connecting rods, 8 and 9, and bearing plates, 10, can be mounted upon the motor shaft and the cutting blades attached to the lugs as described.

Suitable openings, 25', may be formed in the rear faces of the top housing to permit access to the set screws, 16, and facilitate the changes just described.

In the operation of my apparatus, the loaves of bread are placed upon the table or chute, 23, and moved forwardly into contact with the cutting blades, 14, which are reciprocated by the turning of the crank shaft, 5, thus slicing the bread and the travel of the oncoming loaves will carry the sliced loaves on out to the discharge end of the table, 23.

Various modifications may be made without departing from the spirit of my invention, and I do not limit my claims to the precise forms shown in the drawing.

It is obvious that the relative angle of the connecting rods, 8 and 9, and the extent of the offset of the eccentric rings, 6 and 7, may be varied as desired without departing from the spirit of my invention.

In practice it will be found that very little angle from the vertical will be sufficient to permit the tension of the springs, 27, to keep the faces of the bearing plates, 10, in constant contact with the guide rolls, 12, and it is only necessary that sufficient tension be applied thereto to keep contact and prevent a jumping or irregular movement of the guide plates.

Either plain or roller or ball bearings may be used on the eccentrics and the rings, 6 and 7, may completely encircle the eccentrics, 6' and 7', or they may be split or bolted together as in Figure 1.

I claim:

1. A bread slicing machine comprising a housing, a drive shaft mounted therein having opposed eccentrics formed upon both extended ends thereof, a pair of U-shaped frames comprising transverse bearing plates and connecting rods formed integral therewith mounted in intermediately crossed relation upon the eccentrics and adapted to be reciprocated thereby when the eccentrics

rotate, alternating series of lugs formed upon the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, resilient means mounted in the housing and united to the top of the cutting blades tending to exert tension upwardly thereon and to hold the adjacent faces of the bearing plates in continuous contact with the guide rolls, and means to support the bread during the slicing operation.

2. A bread slicing machine comprising a housing, a pair of U-shaped frames comprising transverse bearing plates and connecting arms formed integral therewith mounted in intermediately crossed relation, alternating series of lugs formed upon the inner faces of the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, driving means mounted in the housing to which the connecting arms are united adapted to reciprocate the frames in alternation, and resilient means mounted in the housing and united to the top of the cutting blades tending to exert tension upwardly thereon and to hold the adjacent faces of the bearing plates in continuous contact with the guide rolls.

3. A bread slicing machine comprising a housing, a drive shaft mounted therein having opposed eccentrics formed upon both extended ends thereof, a pair of interchangeable U-shaped frames comprising transverse bearing plates and connecting rods formed integral therewith mounted in intermediately crossed relation upon the eccentrics and adapted to be reciprocated thereby when the eccentrics rotate, alternating series of lugs formed upon the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, resilient means mounted in the housing and united to the top of the cutting blades tending to exert tension upwardly thereon and to hold the adjacent faces of the bearing plates in continuous contact with the guide rolls, and means to support the bread during the slicing operation.

4. A bread slicing machine comprising a housing, a drive shaft mounted therein having opposed eccentrics formed upon both extended ends thereof, a pair of U-shaped frames comprising transverse bearing plates and connecting rods formed integral therewith mounted in crossed relation upon the eccentrics and adapted to be reciprocated thereby when the eccentrics rotate, alternating series of lugs formed upon the bearing plates, a plurality of cutting blades arranged in two series and having their lower ends pivotally secured in the series of lugs respectively,

- 5 stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, and a detachable guide and blade tensioning assembly mounted in the housing and comprising a slotted transverse guide plate, a plurality of supporting rods mounted therein, with resilient means united to the supporting rods and the upper ends of the cutting blades adapted to exert continuous tension upon the cutting blades in an upward direction.

10 5. A bread slicing machine comprising a housing, a drive shaft mounted therein having opposed eccentrics formed upon both extended ends thereof, a pair of interchangeable U-shaped frames comprising transverse bearing plates and connecting rods formed integral therewith mounted in crossed relation upon the eccentrics and adapted to be reciprocated thereby when the eccentrics rotate, alternating series of lugs formed upon the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, and a detachable guide and blade tensioning assembly mounted in the housing and comprising a slotted transverse guide plate, a plurality of supporting rods mounted therein, with resilient means united to the supporting rods and the upper ends of the cutting blades adapted to exert continuous tension upon the cutting blades in an upward direction.

15 6. A bread slicing machine comprising a housing, a pair of U-shaped frames comprising transverse bearing plates and connecting arms formed integral therewith mounted in crossed relation, alternating series of lugs formed upon the inner faces of the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, driving means mounted in the housing to which the connecting arms are united adapted to reciprocate the frames in alternation, a detachable guide and blade tensioning assembly mounted in the housing and comprising a slotted transverse guide plate, a plurality of supporting rods mounted therein, with resilient means united to the supporting rods and the upper ends of the cutting blades adapted to exert continuous tension upon the cutting blades in an upward direction.

20 7. A bread slicing machine comprising a housing, a pair of interchangeable U-shaped frames comprising transverse bearing plates and connecting arms formed integral therewith mounted in crossed relation, alternating series of lugs formed upon the inner faces of the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, driving means mounted in the housing to which the connecting arms are united adapted to reciprocate the frames in alternation, a detachable guide and blade tensioning assembly mounted in the housing and comprising a slotted transverse guide plate, a plurality of supporting rods mounted therein, with resilient means united to the supporting rods and the upper ends of the cutting blades adapted to exert continuous tension upon the cutting blades in an upward direction.

25 8. A bread slicing machine comprising a housing, a drive shaft mounted therein having opposed eccentrics formed upon both extended ends thereof, a pair of U-shaped frames comprising transverse bearing plates and connecting rods formed integral therewith mounted in crossed relation upon the eccentrics and adapted to be reciprocated thereby when the eccentrics rotate, alternating series of lugs formed upon the bearing plates, a plurality of cutting blades arranged in two series and having their lower ends pivotally secured in the series of lugs respectively, stub shafts united to the housing at opposite sides thereof and extending inwardly at the level of the bearing plates, guide rolls rotatably mounted upon the stub shafts and projecting between the inner faces of the opposed bearing plates and adapted to guide the bearing plates, and guide and blade tensioning means mounted in the housing and comprising a slotted transverse guide plate, a plurality of supporting rods mounted therein, with resilient means united to the supporting rods and the upper ends of the cutting blades adapted to exert continuous tension upon the cutting blades in an upward direction.

30 9. In a bread slicing machine having a housing with reciprocating cutting blades mounted therein, a detachable blade supporting, driving and tensioning unit comprising a pair of U-shaped frames detachably mounted upon and adapted to be driven by eccentrics, a plurality of cutting blades arranged in two alternating series having their lower ends pivotally united to the respective frames in series, a guide plate detachably mounted in the housing, slots formed in the guide plate adapted to receive and guide the upper end of the cutting blades, a plurality of supporting rods seated in the guide plate extending upwardly therefrom, and resilient means attached to the upper ends of the rods and to the upper ends of the cutting blades adapted to continuously exert tension upwardly upon the cutting blades.

35 10. In a bread slicing machine having a housing with reciprocating cutting blades mounted therein, a detachable blade supporting, driving and tensioning unit comprising a pair of U-shaped frames detachably mounted upon and adapted to be driven by a drive shaft, a plurality of cutting blades arranged in two alternating series having their lower ends pivotally united to the respective frames in series, a guide plate detachably mounted in the housing, slots formed in the guide plate adapted to receive and guide the upper end of the cutting blades, a plurality of supporting rods seated in the guide plate extending upwardly therefrom, and resilient means attached to the upper ends of the rods and to the upper ends of the cutting blades adapted to con-

tinuously exert tension upwardly upon the cutting blades.

11. In a bread slicing machine having a housing and a plurality of cutting blades reciprocatingly mounted therein, a detachable guide and blade tensioning assembly mounted in the housing and comprising a slotted transverse guide plate, a plurality of supporting rods mounted therein corresponding to the number of blades, 10 and separate resilient means united to each of the supporting rods severally and to the upper end of its corresponding cutting blade adapted to exert continuous tension thereon in an upward direction.
12. In a bread slicing machine having a housing and a plurality of cutting blades reciprocatingly mounted therein, a detachable guide and blade tensioning assembly mounted in the housing and comprising a slotted transverse guide 20 plate, a plurality of supporting rods mounted therein, corresponding to the number of blades, and separate tension springs having their upper ends united to the supporting rods severally and their lower ends united to the upper ends of the 25 cutting blades.
13. A bread slicing machine comprising a housing, a drive shaft mounted therein having opposed eccentrics formed upon both extended ends thereof, a pair of U-shaped frames comprising transverse bearing plates and connecting rods 30 formed integral therewith mounted in intermediate crossed relation upon the eccentrics and adapted to be reciprocated thereby when the eccentrics rotate, alternating series of lugs formed

upon the bearing plates, a plurality of cutting blades arranged in two series and having their lower ends pivotally secured in the series of lugs respectively, guides united to the housing at opposite sides thereof projecting between the inner faces of the opposed bearing plates and adapted to guide the bearing plates, and resilient means mounted in the housing and united to the top of the cutting blades tending to exert tension upwardly thereon and to hold the adjacent faces of the bearing plates in continuous contact with the guides, and means to support the bread during the slicing operation. 5 10

14. A bread slicing machine comprising a housing, a pair of U-shaped frames comprising transverse bearing plates and connecting arms formed integral therewith mounted in intermediate crossed relation, alternating series of lugs formed upon the inner faces of the bearing plates, a plurality of cutting blades arranged in two series and having their lower ends pivotally secured in the series of lugs respectively, guides united to the housing at opposite sides thereof and extending inwardly between the inner faces of the opposed bearing plates and adapted to 25 guide the bearing plates, driving means mounted in the housing to which the connecting arms are united adapted to reciprocate the frames in alternation, and resilient means mounted in the housing and united to the top of the cutting blades 30 tending to exert tension upwardly thereon and to hold the adjacent faces of the bearing plates in continuous contact with the guides. 25

HARRY J. CRINER.
